(57) **CLAIM**

The ornamental design for a single-phase capacitor switch, as shown and described herein.

DESCRIPTION

FIG. 1 is a front view of the single-phase capacitor switch. FIG. 2 is a side view of the single-phase capacitor switch shown in FIG. 1.

FIG. 3 is a top view of the single-phase capacitor switch shown in FIG. 1; and,

FIG. 4 is a bottom view of the single-phase capacitor switch shown in FIG. 1.

The broken line showing of the environment is for illustrative purpose only and forms no part of the claimed design.
